MECHANICAL HAMMER

Benjamin W. Snodgrass, Denver, Colo.

Application March 24, 1936, Serial No. 70,579

15 Claims. (Cl. 255—42)

This invention relates to mechanical hammers of self-contained type wherein a prime mover is operatively associated with and for actuation of a ram element in a single, portable unit, and has 5 as an object to provide an improved construction and arrangement of elements constituting such a unit.

A further object of the invention is to provide an improved self-contained mechanical hammer 10 unit of enhanced operative efficiency.

A further object of the invention is to provide improved means operatively interconnecting a prime mover and a reciprocable ram in a mechanical hammer unit.

15 A further object of the invention is to provide improved speed-controlled means automatically operable to interconnect a reciprocable ram and a prime mover for uniform actuation of said ram.

A further object of the invention is to provide 20 improved means automatically operable to actuate a reciprocable ram in a mechanical hammer in a definite, timed cycle.

A further object of the invention is to provide 25 improved means automatically operable to interconnect a reciprocable ram and a prime mover in a mechanical hammer for actuation of said ram in a definite, timed cycle.

A further object of the invention is to provide 30 an improved mechanical hammer unit comprising a ram freely reciprocable between elastic abutments, a prime mover, and speed-controlled means automatically operable to connect said ram and prime mover for actuation of the latter in a definite, timed cycle.

35 A further object of the invention is to provide an improved mounting for a reciprocable ram in a mechanical hammer.

A further object of the invention is to provide 40 an improved operative connection between a reciprocable ram and a rotary driving element in a mechanical hammer.

A further object of the invention is to provide 45 improved speed-controlled clutch means operatively between a reciprocable ram and a prime mover in a mechanical hammer and automatically operable to limit actuation of said ram to a definite, timed cycle.

A further object of the invention is to provide 50 an improved mechanical hammer unit of simple, relatively inexpensive construction, susceptible of embodiment in a single, compact unit, adapted for practical use in a wide variety of specific fields, and arranged for operative actuation with enhanced efficiency.

55 My invention consists in the construction, ar-

rangement and combination of elements herein-after set forth, pointed out in my claims, and illustrated by the accompanying drawings, in which—

Figure 1 is a side elevation of a hammer construction embodying the principles of my invention as assembled and arranged for practical use. Figure 2 is a section axially of the construction shown in Figure 1, certain elements being broken away to conserve space. Figure 3 is a cross section, on an enlarged scale, taken on the indicated line 3—3 of Figure 2. Figure 4 is a cross section similar to Figure 3, taken on the indicated line 4—4 of Figure 2. Figure 5 is a cross section similar to Figures 3 and 4, taken on the indicated line 5—5 of Figure 2. Figure 6 is a section axially of a hammer construction modified somewhat relative to the showing of Figure 2. Figure 7 is a cross section, on an enlarged scale, taken on the indicated line 7—7 of Figure 20 5

6. Figure 8 is a cross section taken on the indicated line 8—8 of Figure 6. Figure 9 is a fragmentary, detail section axially of an elastic abutment and related element employed in the improved construction. Figure 10 is a fragmentary, 10 detail section, on an enlarged scale, axially through the connection between a ram element and its actuating element. Figure 11 is a fragmentary, detail section similar to Figure 10 and illustrating a somewhat modified construction 15

and relation of the elements shown in Figure 10. Figure 12 is a section axially of a yet further modified practical embodiment of the improved 20 hammer. Figure 13 is a cross section, on an enlarged scale, taken on the indicated line 13—13 of Figure 12. Figure 14 is a cross section similar 25 to Figure 13, taken on the indicated line 14—14 of Figure 12. Figure 15 is a fragmentary, detail section, on an enlarged scale, axially through certain actuating elements and connections employed in the improved hammer. Figure 16 is a 30 fragmentary, detail section, on an enlarged scale, axially of a relatively rotatable connection employed in the improved hammer. Figure 17 is an elevation of an automatic, speed-controlled clutch 35

assembled employed in the improved hammer unit and showing said clutch in its disengaged relation. Figure 18 is an elevation similar to Figure 17 illustrating the clutch elements of the latter figure in their engaged or driving relation. 40

In the construction of the improvement as shown, a suitable unitary frame supporting and housing the various elements of the hammer assembly is illustrated as comprising a plurality 45

of tubular sections 20, 21 and 22 suitably inter-

55

50

55

connected, as by means of bolts engaging through annular flanges on adjacent ends of said sections, in axial alignment to form a rigid assembly. The outer end of the section 22 is suitably arranged 5 to engage with and be removably secured to the housing 23 of an electric motor, or equivalent prime mover, whereby the driving shaft 24 of the prime mover is disposed at one end of and in axial alignment with the tubular housing assembly. While the tool assembly is shown 10 throughout in operative association with an electric motor, it is to be understood that other equivalent and suitable sources of power may be substituted for the electric motor shown without 15 in any way departing from the principles and spirit of the invention.

The tubular housing section 21 is relatively long and defines a straight cylindrical chamber wherein a ram element 25, of suitable mass, is 20 mounted for actuation longitudinally of the assembly. Various specific mountings for the ram 25 are illustrated in the drawings. As shown in Figures 2 and 3, the ram 25 is formed as a cylindrical element of a size to fit loosely within its 25 chamber in the housing 21 and is provided with a plurality of longitudinal ribs 26 extending substantially the length of the ram and projecting in uniformly-spaced relation radially from the outer surface of said ram, said ribs being grooved 30 longitudinally of their outer faces for engagement with balls 27, or equivalent anti-friction devices, carried by retainer elements 28 adjustably engaging radially through the housing member 21. The retainer elements 28 are preferably 35 grouped in two longitudinally spaced assemblies circumferentially of the member 21, and thereby provide mountings adjacent the opposite ends of the ram 25 wherein said ram may reciprocate freely and be retained against rotary motion relative to the member 21. As shown in Figures 6 40 and 8, the ram 25 provided with the ribs 26 is mounted by means of the balls 27 and retainer elements 28 for axial reciprocation longitudinally of and within a tubular sleeve 29, which latter is 45 mounted for rotation within and fixed against travel longitudinally of the housing member 21 by means of anti-friction ball bearing assemblies 50 30 engaging between end portions of the sleeve 29 and annular races disposed in spaced relation within the housing member 21, thus mounting the ram 25 for both rotation and axial reciprocation relative to said housing member. As 55 shown in Figures 12 and 13, the ram mounting comprises enlarged annular bosses 31 adjacent the ends of the ram 25 wherein relatively wide and deep ways 32 are formed in alignment longitudinally of the ram, anti-friction ball bearing assemblies 33 rotatably supported in axially radial relation within the housing member 21 being 60 positioned to engage within the ways 32 at each end of the ram 25 to rollingly support the latter for reciprocation axially of said housing member. While the construction according to Figures 12 and 13 provides for non-rotatable reciprocation 65 of the ram 25, it is to be understood that the roller bearing assemblies 33 could conveniently be carried in fixed relation with a sleeve 29 which is in turn mounted for rotation within the housing member 21, thus providing a rotatable reciprocable mounting for the ram 25 corresponding 70 in function with the arrangement shown in Figures 6 and 8.

The ram 25 is arranged for power actuation deriving from the prime mover assembly 23 between elastic abutments disposed adjacent the

opposite ends of the member 21, the abutment adjacent the power end of the assembly being illustrated in the form of an expansive coil spring 34 carried by a suitable cup-like retainer 35 disposed within the member 21 to bear against an 5 end flange of said member and thereby position the spring 34 in axial alignment with the ram 25 and in position to engage against the adjacent end of said ram as the latter is moved toward the power end of the assembly. An annular recess 10 is formed in the housing member 20 in communicating relation with the adjacent end of the member 21 to house and support an impact head and spring assembly comprising the other of the elastic abutments. As shown, a frusto-conical 15 spring element 36 is seated with its base engaging against the inner end of the annular recess in the housing member 20 and is thereby positioned in axial alignment with the ram 25, the smaller end of the conical spring 36 bearing against a 20 piston-like impact head 37 slidably sealed within a bearing sleeve 38 fitted within said annular recess and provided with a retaining rib 39 engaging that face of the impact head adjacent the ram to limit travel of said head in one direction, 25 the said impact head being thus axially aligned with the ram 25 and positioned for engagement at times by the adjacent end of said ram. On the spring side of the impact head 37 the housing 20 is formed with an axial bore opening outwardly through the end of the housing assembly from the annular recess containing the impact head, which bore is adapted to slidably receive and support the shank 40 of a tool element operatively associated with the hammer assembly, the 30 inner end of said shank 40 extending within said bore and through the conical spring 36 to engagement with the adjacent face of the head 37, which latter then acts to transmit impact of the 35 ram 25 to work effect on said tool. 40

Power actuation of the ram 25 is had through the agency of an axially-disposed stem 41 engaged at one end with the end of the ram adjacent the spring 34 and projecting through the adjacent end of the housing member 21 into the 45 housing member 22. The specific connection between the stem 41 and ram 25 will vary according to the specific mounting of the ram within its housing member 21, since the stem 41 is arranged to be rotatably as well as axially actuated. When 50 the ram 25 is mounted for rotation as well as axial reciprocation, the stem 41 may be fixedly engaged with said ram through the agency of a connection such as is illustrated in Fig. 10; however, when the ram is non-rotatably mounted, the connection between said ram and the stem 41 must be such as will permit of relative rotation therebetween, a swivel joint effective to permit of such relative rotation being illustrated in Figure 11 as comprising an annular rib 42 projecting in fixed 55 relation inwardly of one end of the ram 25 for operative engagement with complementary bearing plates 43 removably carried by the corresponding end of the stem 41. An annular cam track 44 is fixed to the end of the housing member 21 within the adjacent member 22 in concentric relation with the stem 41 and is disposed with the peaks of its cam lobes directed toward the power end of the assembly, and said stem 41 is provided with a cam follower 45 rotatably mounted 60 in anti-friction bearings carried by said stem and disposed in axially-perpendicular, fixed relation with said stem to engage against and traverse the cam track 44. With the foregoing arrangement, 65 rotation of the stem 41 acts to move the follower 70 75

45 about the cam track 44 to effect axial displacement of the stem 41 and ram 25 in accordance with the number and shape of the cam lobes carried by said track, said lobes being so arranged 5 as to permit full driving engagement of the ram against the impact head 37 and tool shank 40 at one extreme and to accelerate the ram 25 to engagement with the spring 34 at the other extreme, the cam lobes consequently having a relatively 10 moderate approach inclination to their peaks in the direction of rotation and dropping off rapidly to the point of greatest cam depth after the cam peak has been passed. To effect power rotation of the stem 41, a power transmission 15 shaft 46 is journaled for rotation in the housing member 22 in axial alignment with said stem 41 and driving connection between said shaft 46 and stem 41 is had through complementary, telescoping coupling elements 47 and 48 fixed respectively to the shaft 46 and stem 41 and operatively interconnected by means of anti-friction 20 balls 49 adjustably supported by retainers 50 mounted radially through the coupling element 47 for engagement within grooves 51 disposed longitudinally of the coupling element 48, thereby 25 providing a rotatably-engaged, axially-variable positive drive between the shaft 46 and stem 41.

In the construction shown in Figures 12 to 16, inclusive, the driving connection between the shaft 46 and stem 41 is in all functional respects identical with but differs structurally from that above described. As shown in the figures last noted, the shaft 46 fixedly carries a coupling element 47' which supports individually-rotatable anti-friction bearing assemblies 52 axially fixed in uniformly-spaced relation radially of said element, which bearing assemblies are adapted to operatively engage in longitudinal ways 53 formed in the periphery of the complementary coupling 30 element 48' carried by the stem 41 in telescoping relation with the coupling element 47'. The coupling element 48' is preferably mounted for rotation on and fixed against displacement axially of the end of the stem 41 by means of suitable anti-friction bearing assemblies 54, as shown in Figure 16, and is provided with an integral axial hub 55 spaced from and surrounding the stem 41 and directed toward the adjacent end of the housing member 21. The free end of the hub 55 is provided with suitably spaced and contoured cam lobes directed toward the ram 25, which lobes are adapted to engage against and ride on fixed, rotatable cam followers 56 supported by and projecting radially within a flanged sleeve 57 fixed 40 to the end of the housing member 21 within the member 22 in concentric relation with said stem 41.

Since the ram 25 is free for longitudinal reciprocation between its elastic abutments and is 45 mechanically limited in such reciprocation solely by the cam track and follower arrangement employed, it is obvious that for efficient actuation of the ram the cam track and follower arrangement should be so designed with reference to the operative speed imparted thereto as to engage 50 for acceleration of the latter from the impact head 37 and to release said ram for opposite travel deriving from the spring 34 in time to free said ram from any mechanical restraint imposed by cam track and follower engagement during 55 such spring-impelled travel. As a consequence, it follows that for every specific combination of given ram actuatable between given abutments under the influence of a given speed of drive there is 60 but one cam track and follower arrangement

which will function to produce the desired smooth, uniform acceleration and operation of the ram resulting from the application of power impulses accurately synchronized with the recoil velocities resulting from reaction between said ram and said abutments, and, conversely, that for a given cam track and follower arrangement in operative combination with a given arrangement of ram and elastic abutments there is but one operative speed for the cam track and follower arrangement which will be productive of smooth, uniform, synchronized ram actuation between and for reaction from the said abutments. While the shaft 46 could be directly connected to the driving element of the prime mover in constant driving relation with the ram 25 irrespective of the operative speeds of said prime mover, such actuation of the ram would be smooth and efficient only at one driven speed and would be productive of excessive vibration in the assembly, 10 inefficient power delivery by the ram, and rapidly destructive loads on operating elements of the assembly at speeds of the prime mover other than the one for which such elements have been designed, such inefficient operation being particularly and inevitably present during the speed variation consequent upon starting and stopping of the prime mover. To insure actuation of the ram with only that prime mover speed for which a cam assembly has been designed, and to provide 15 means adjustable to preserve operative synchronization between ram actuation and prime mover speeds, operative connection between the driven shaft of the prime mover and the shaft 46 is had through an automatically speed-controlled clutch 20 unit illustrated in one specific embodiment in Figures 6, 17, and 18.

In the construction shown, which is but a typical embodiment of functionally equivalent arrangements, the shaft 24 is shown in fixed, driving 25 relation with a concentric plate 58 positioned within one end of the housing member 22 in adjacent registration with the open end of a cylindrical, hollow drum 59 carried in fixed, concentric relation on the adjacent end of the shaft 46. The plate 58 is free to rotate with the driven shaft of the prime mover independently of the drum 59 and carries a substantially circular, expansive clutch band 60 pivotally fixed at one end, as at 61, adjacent a margin of the plate to register with the periphery of said plate and project perpendicularly from the surface of said plate in closely spaced, concentric relation with the inner cylindrical surface of and within the drum 59, so that expansion of the clutch band 60 serves to engage the outer surface of said band with the inner surface of said drum for clutched, simultaneous rotation of said elements. For automatic, speed-controlled actuation of the clutch band 60, a weighted lever 62 is pivotally engaged at one end, 30 as indicated at 63, with the free end of the clutch band and is pivotally mounted on the plate 58 by means of a pin or support 64 engaging through said lever 62 with said plate eccentrically of the latter and in spaced, adjacent relation with the pivotal connection 63, thus disposing the weighted, major portion of the lever 62 eccentrically across the plate 58 and in position to swing outwardly of said plate about its pivotal mounting 64 under the influence of centrifugal force to separate the free and fixed ends of the clutch band 60 and expand said band into clutched engagement with the drum 59. To limit and restrain actuation of the lever 62 at relatively low speeds, a lug 65 is fixed to the plate 58 in adjacent, spaced re- 35

lation with the free end of said lever 62, and a retractile coil spring 66 engages between said lug 65 and lever 62 to normally urge the latter inwardly of the plate 58 and to maintain the clutch band 60 in its contracted position. Since it is desired to expand the clutch band 60 into engagement with the drum 59 at a certain, definite rotational speed only, the lever 62 is normally latched against outward movement relative to the plate 58 by means of a hooked spring arm 67 fixed at one end to the lug 65 and extending therefrom to engagement of its free hooked end within a notch 68 formed adjacent the free end of the lever 62, said hook and notch being related for automatic interengagement when the lever 62 is moved inwardly of the plate 58 under the influence of the spring 66. Means operable to release the spring 67 from its hooked engagement with the notch 68 at a definite rotary speed of the assembly are provided in the form of a weighted arm 69 pivotally engaged at one end with a pin or support 70 disposed eccentrically across said plate on the opposite side of the plate center from the lever 62, the free end of the arm 69 being arranged to engage against the free end of the lever 62, when said elements are in their innermost positions relative to the plate 58. The arm 69 is adjustably and yieldably held in normal engagement of its free end with the end of the lever 62 by means of an expansive coil spring 71 engaging between said arm and a stud 72 fixedly carried by the plate 58, a threaded arm 73 projecting radially from said stud 72 engaging within the spring 71 and supporting an adjusting nut 74 in bearing engagement against the end of said spring for adjustable variation in the pressure exerted by said spring on the arm 69. A finger 75 is fixedly carried by the free end of the arm 69 in position to bear against the spring 67 and is so adjusted in length as to permit hooked engagement of the spring 67 with its notch 68 when the ends of the lever 62 and arm 69 are engaged, and to move outwardly against and flex the spring 67 for release of its hooked engagement with the notch 68 when the arm 69 is moved about its pivot and against the pressure of its spring 71 under the influence of centrifugal action deriving from rotation of the plate 58. With the foregoing arrangement, it is obvious that the pressure of the spring 71 may be so adjusted as to permit outward motion of the arm 69 with a predetermined angular velocity of the plate 58, which motion of the arm 69 acts to release the spring 67 from its latched engagement with the lever 62 for outward, centrifugally-influenced travel of the latter and consequent clutched engagement of the band 60 with the drum 59, any decrease in the centrifugal force permitting the inherent tension in the clutch band 60 and the influence of the spring 66 to return the lever 62 inwardly of the plate 58 for renewal of the latched, inoperative relation of the clutch assembly elements as shown in Figure 17.

The clutch arrangement just described constitutes speed-controlled means automatically operable to engage and actuate the ram 25 and associated mechanism when the prime mover has attained a given rotational speed, the clutch assembly being so adjusted as to engage at that driving speed of the prime mover for which the ram and cam and follower arrangement has been designed, the prime mover being so constructed or governed as to operate under load at a constant and uniform speed. With the clutch assembly operatively engaging between the prime mover

and the shaft 46, ram actuation is had only at that driving speed for which the mechanism has been timed, and the ram is inoperative during starting and stopping phases of the prime mover operation and during decrease of prime mover driving speed deriving from variations in power or load factors, thus insuring smooth and highly efficient operation of the tool assembly and eliminating the danger of excess wear and damage resulting from unsynchronized ram actuation. 10

In drilling operations it is generally desirable that the drill tool be rotated while it is being driven, and it has been determined that when the ram 25 of the improved hammer is mounted for rotation as well as reciprocation the angular velocity of the ram during its engagement with the impact head 37 is sufficient to rotate said impact head and the tool engaged thereby to the extent desirable in the operation, but when the ram 25 is held against rotation, it may be desirable to include in the hammer assembly some such mechanical arrangement as is shown in Figures 1 and 2 to automatically and positively rotate the tool. As shown in the figures last noted, the housing member 20 is formed to receive and rotatably support a sleeve 76 disposed in axial alignment with the tool shank 40 and arranged to slidably receive said tool shank to engage ribs or fins 77 projecting radially in fixed relation from said shank for rotational driving engagement between said sleeve and the tool element. A gear 78 is fixed in concentric relation with the sleeve 76 and meshes through an opening in the housing member 20 with a gear 79 frictionally associated in driven relation with a shaft 80 disposed in axial parallelism with the ram 25 and shaft 46 and journaled for rotation in suitable bearings carried by the housing members 20, 21, and 22. The shaft 46 is provided with a crank element 81 arranged to cooperate with and actuate ratchet detents 82 projecting through the housing member 22 for operative engagement with a ratchet pinion 83 fixed to the shaft 80, which arrangement permits step by step rotation of the shaft 80, gear 79, gear 78, sleeve 76 and the engaged tool element 40 deriving from rotation of the shaft 46 and yieldable without damage to the actuating elements when the tool is jammed or bound against rotation through the frictional driven mounting of the gear 79 on the shaft 80. As shown in Figures 1 and 2, the end of the housing member 20 may be closed by means of a removable cap 84 through which the tool element is freely slidable, and a suitable hook member 85 may be hinged to said cap to hold the tool element against escape from the hammer assembly, as is common practice. In certain drilling operations it is desirable to jet water through the drill tool and outwardly of the working face of such tool, to which end the improved hammer assembly may readily be adapted by the mounting of a suitable pump assembly 86 in driven relation with the prime mover for connection of its intake 87 with a suitable source of water supply and for operative connection of its outlet through a suitable conduit 88 engaging through the housing member 20 with an annular groove exteriorly of the impact head 37 and in sealed relation with the sleeve 38, a radial passage 89 in the impact head 37 communicating between said annular groove and an axial passage 90 formed in said head in registering alignment with the longitudinal bore 91 of the tool element to provide a continuous passage for liquid delivered by the pump 75

86 through the tool element and to the working face of the latter.

Since many changes in the specific form, construction and arrangement of the elements shown 5 and described may be had without departing from the spirit of my invention, I wish to be understood as being limited solely by the scope of the appended claims rather than by any details of the illustrative showing and foregoing description.

10 I claim as my invention—

1. A mechanical hammer comprising a reciprocable ram, a power unit, and speed-controlled means automatically operable to connect said power unit in actuating relation with said ram.

15 2. A mechanical hammer comprising a reciprocable ram, a power unit, and means including an automatic, speed-controlled clutch engaging between and arranged to periodically transmit power acceleration from said power unit to said ram.

20 3. A mechanical hammer comprising a ram reciprocable between spaced abutments and timed for actuation through a synchronous cycle, a power unit in actuating relation with said ram, and means automatically operable to limit operative

25 connection between said ram and power unit to driving speed of the latter synchronized with the operative cycle of said ram.

30 4. A mechanical hammer comprising a ram reciprocable between spaced abutments, cam means operable to actuate said ram through a synchronous cycle, a power unit in actuating relation with said cam means, and means engaging between said power unit and cam means automatically operable to limit engagement therebetween to speeds of said power unit synchronized with the operative cycle of said ram.

35 5. In a mechanical hammer, a reciprocable ram, a power unit arranged to actuate said ram, and automatic, speed-controlled clutch means 40 engaging between said power unit and ram.

45 6. In a mechanical hammer, a ram timed for reciprocation through a synchronous cycle between spaced abutments, a power unit, means operatively connecting said power unit and ram, and means automatically operable to limit the operative connection between said power unit and ram to speeds of the former synchronized with the operative cycle of the latter.

50 7. In a mechanical hammer, a ram element mounted for free reciprocation through a synchronous cycle between spaced abutments, a power unit, means operable to periodically transmit power acceleration from said unit to said ram, and speed-controlled means automatically 55 operable to limit operative connection between said power unit and actuating means to speeds of said unit synchronized with the operative cycle of said ram.

59 8. In a mechanical hammer having a reciprocable ram and a power unit arranged to actuate said ram, means operatively interconnecting said ram and power unit and automatically operable to limit operative connection therebetween to a predetermined speed range of said power 65 unit.

9. In a mechanical hammer, a reciprocable ram, cam track and follower means relatively

rotatable to actuate said ram, a power unit, and automatic, speed-responsive clutch means adapted to operatively engage said power unit and ram actuating means at predetermined speeds of the former.

10. In a mechanical hammer, a ram mounted for rotation and axial reciprocation, a relatively fixed cam track, a cam follower carried by said ram and arranged to traverse said track during rotation and for reciprocation of said ram, a power unit adapted to rotate said ram, and automatic, speed-responsive means engaging said power unit and ram for operative interconnection thereof at predetermined speeds of said power unit.

15 11. In a mechanical hammer, a reciprocable ram, a cam track rotatably carried in fixed axial relation by said ram, relatively fixed cam follower means engageable by said cam track for reciprocation of said ram, a power unit in driving relation with said cam track, and automatic, speed-responsive means intermediate said power unit and cam track adapted to limit operative engagement therebetween to predetermined speeds of said power unit.

20 12. In a mechanical hammer, a reciprocable ram, a power unit, cam and follower means engageable by said power unit to actuate said ram, and normally-disengaged, speed-responsive clutch means intermediate said power unit and ram actuating means arranged to effect engagement therebetween at predetermined speeds of the former.

25 13. In a mechanical hammer having a reciprocable ram and means rotatable to actuate said ram, a power unit operatively engageable with said ram actuating means and a normally-disengaged, speed-responsive clutch operatively associated with said power unit and adapted to automatically engage said ram actuating means 30 at predetermined speeds of said unit.

35 14. In a mechanical hammer having a reciprocable ram, means rotatable to actuate said ram and a power unit engageable with said ram actuating means, a clutch drum operatively associated with said ram actuating means, a clutch band in driven relation with said power unit spaced concentrically within said drum, and speed-responsive means operable to expand said band into clutched engagement with said drum 40 at predetermined speeds of said power unit.

45 15. In a mechanical hammer having a reciprocable ram, means rotatable to actuate said ram and a power unit engageable with said ram actuating means, a clutch drum operatively associated with said ram actuating means, an expansive clutch band in driven relation with said power unit concentrically within said clutch drum, speed-responsive means operable to expand said band into clutched engagement with said drum 50 at predetermined speeds of said power unit.

BENJAMIN W. SNODGRASS.
